BOTTLE FILLING MACHINE.

(Application filed Dec. 1, 1899.)

(No Model.)

UNITED STATES PATENT OFFICE.

SAMUEL C. MILLER, OF LOUISVILLE, KENTUCKY.

BOTTLE-FILLING MACHINE.

SPECIFICATION forming part of Letters Patent No. 654,016, dated July 17, 1900.

Application filed December 1, 1899. Serial No. 738,888. (No model.)

To all whom it may concern:

Be it known that I, SAMUEL C. MILLER, a citizen of the United States, and a resident of Louisville, in the county of Jefferson and State 5 of Kentucky, have invented certain new and useful Improvements in Bottle-Filling Machines, of which the following is a full, clear, and exact description.

This invention relates to improved bottle- 10 filling machines employing a vertically-movable liquid-holder, spaced filling-tubes depending therefrom to enter the necks of bottles placed beneath said tubes to receive liquid therethrough, and means to cut off the flow 15 of liquid when the bottles are filled.

The object of my invention is to provide novel, simple, and conveniently-arranged details of construction in a machine of the character indicated whereby the liquid passing 20 into one or more bottles is more accurately controlled than in machines of this character as heretofore constructed, and a practical efficiently-operating machine is provided which is devoid of complicated parts, is readily operated by unskilled labor, is rapid in action, 25 and which may be manufactured at a moderate cost.

The invention consists in the novel construction and combination of parts, as here- 30 inafter described, and defined in the appended claims.

Reference is to be had to the accompanying drawings, forming a part of this specification, in which similar characters of reference indicate corresponding parts in all the figures.

Figure 1 is a partly-sectional front elevation of the improved bottle-filling machine. Fig. 2 is a partly-sectional side view of the same substantially on the line 2 2 in Fig. 1.

Fig. 3 is an enlarged longitudinal sectional view of a liquid-holder and attachments thereto substantially on the line 3 3 in Fig. 1. Fig. 4 is an enlarged longitudinal sectional view of the same substantially on the line 4 4 in Fig. 1. Fig. 5 is an enlarged fragmentary sectional side elevation of a modified construction of one of the bottle-filling tubes and of a peculiarly-formed bottle-neck wherein the tube is inserted, and Fig. 6 is an en- 45 larged sectional plan view of a portion of the machine-frame substantially on the line 6 6 in Fig. 1.

In the drawings, 7 indicates the liquid-holding tank wherein is held the liquid which is to be bottled, said tank comprising an elongated nearly-rectangular receptacle having the lower portion contracted laterally, so as to direct the contents toward the transverse center thereof, and the upper portion covered by a sealed cap-piece 7^a, secured thereto by 50 bolts or equivalent means.

Upon the ends of the tank 7 are adjustably secured two similar guide-bars 8, so as to depend therefrom in parallel planes, and said bars are rendered changeable in position by 55 employing the securing-bolts *a*, which may be entered and held secured in pairs of spaced perforations *b*, formed in series in the upper portion of each guide-bar, which manner of connecting the guide-bars upon the ends of the tank permits the latter to be raised or lowered with regard to other parts of the machine. The guide-bars 8 are positioned oppositely and have a loose sliding engagement with undercut flanges *c*, formed or secured 70 on the vertical standards 9, which are opposite side members of a main supporting-frame 10, whereon are located the entire details of the machine, said frame being a substantially-rectangular structure having four legs and 75 sufficient height for the proper elevation of the working parts sustained thereon.

In the guideways *d*, oppositely formed upon the inner surfaces of the frame 10, a table 11 is held to slide in a horizontal plane longitudinally thereof, and on the lower side of the table at a suitable point a toothed rack 12 is formed or secured so as to extend lengthwise, the rack preferably being made equal in length with that of the table, as shown in 80 Fig. 2.

On a transverse shaft 13, journaled in the frame-standards 9, a pinion 14 is secured and has meshed engagement with the rack 12, a hand-wheel 14^a, secured upon an outwardly- 85 extended end of the shaft 13, affording means for its rotation and the consequent sliding movement of the table 11, that by manipulation of the hand-wheel may be moved toward either end of the frame, as may be required. 90 A transverse four-limbed brace-piece 15 is attached at its several ends, respectively, upon side portions of the main frame 10 to stiffen said frame. Another cross-bar 16 is provided

having angle-braces 16^a, said cross-bar having its ends, as well as the ends of the angle-braces, secured upon the depending guide-bars 8. The connected guide-bars 8 and the tank 7, from which they depend, are held normally in elevated position on the standards of the frame 10 by the contractile force of one or more springs 17, that at their lower ends are attached to a treadle-lever 18 and at their upper ends to projections from the frame 10. The treadle-lever 18 is pivoted at one end upon the frame 10 and projects at the opposite end outward sufficiently to receive foot-pressure, said lever having a series of spaced holes *e* formed therein intermediately of its ends to enable the adjustable connection therewith of the lower end of a link-bar 19 by means of a pivot-bolt or the like, the upper end of said link-bar having a like connection with the cross-bar 16, the connection of the lower end of the link-bar with the treadle permitting the latter to receive adjustment for raising or lowering the free end thereof to facilitate the effecting of more or less depression of the tank 7, as may be desired.

It will be seen that a U-shaped guide-piece 20 is secured upon a transverse lower member of the frame 10 and depends therefrom to loosely embrace the free end portion of the treadle-lever 18, a series of opposite perforations formed in each limb of the guide-piece 20 for the reception of a transverse pin 21 permitting the latter to be changed in position, and thus limit the downward movement of the treadle-lever to an exact point, which is very essential for the proper operation of the apparatus, as will be further explained. A buffer-spring *g* is held upon the frame 10 directly above the free portion of the treadle-lever 18 and cushions the impact of said lever when foot-pressure is relaxed thereon, and the tension of the spring or springs 17, which have been expanded, serves to lift the lever into normal position.

45 A series of spaced filling-tubes 22 is located in the tank 7, said tubes being arranged in a straight row lengthwise of the tank in the same vertical plane, and consequently cross-wise of the table 11, above which they are held depending from the lower side of the tank. As the filling-tubes are of like form and construction, a description of one tube and its adjuncts will be sufficient for all of said tubes.

55 Referring to Fig. 3, wherein one of the filling-tubes 22 is sectionally represented, it will be seen that each tube comprises a straight pipe of proper diameter and length, slightly contracted at its lower end and having a sealing-cap *h* secured on or in the upper end thereof. An air-escape pipe 23 of small diameter is located in each tube 22 and is bent laterally at each end, preferably in the same direction, these bent ends *i* *i'* being respectively secured in perforations in the side of the tube 22, near the upper and lower end of the same. A cup-like recess or depression 7^b

is formed in the cap-piece 7^a to receive the upper end of each filling-tube 22, that is upwardly inserted therein through an orifice at 7^c the center of said cup; and a sealing-cover 7^e is secured over each cup, preferably having dome shape, as shown in Fig. 3. The upper end of the filling-tube 22 projects through a perforation in the bottom wall of a respective 75 depression 7^b a sufficient distance to locate the open end *i* of the air-escape pipe 23 at all times within said depression, and a plurality of openings *i'*, formed in this bottom wall at the side of the centrally-located filling-tube, 80 serve to connect the depression 7^b with the upper portion of the tank 7. The air-inlet *i'* at the lower end of the air-pipe 23, being above the outlet of the filling-tube, prevents the air from catching up the liquid and clogging said pipe. By arranging the air-escape pipe 23 in the filling-tube 22 with its ends opening out through the sides of the tube, near the ends thereof, provision is made for 85 clearing said pipe of liquid, and thereby preventing the slow dripping of the liquid therefrom, as hereinafter more fully described. The lower bent end of the air-escape pipe 23 is inserted through or into a perforation laterally formed in the side wall of the filling-tube 22, near the lower end of the latter, and thus provides an air-inlet *i*² for the lower end of the pipe 23. A stuffing-box 7^d is secured in the narrow lower wall of the tank 7 in the same vertical plane with the center of each 90 depression 7^b, and the filling-tube which passes up into each depression 7^b extends down through the stuffing-box, and it will be seen that the support thus afforded to each filling-tube 22 adapts it to slide vertically 95 and be prevented from lateral displacement. A collar *k* is secured upon each filling-tube 22 at a suitable point below the bottom wall of the depression 7^b, occupied by its upper end portion, and between said collar and the 100 bottom wall of the depression 7^b a coiled spring 24 is placed upon the filling-tube.

At a proper distance below the collar *k* in each filling-tube 22 one or more inlet-orifices *m* are formed in the side thereof, and in the upper side of the stuffing-box 7^d an annular depression *m'* is formed that encircles the tube 22 at the orifice named. Directly above the inlet-orifice *m* a sealing-valve *n* is affixed upon each filling-tube 22, and the valves may be formed of any suitable material which will effect an air and liquid tight closure of the inlet-orifice *m* when the tubes are lowered by pressure of the springs 24, which effect the seating of the valves *n* in the annular channels or depressions *m'*, this being the normal position of the valve, although the valve *n* (shown in Fig. 3) is represented as raised from the seat *m'*, which is done for clearness in illustrating the details of the device. 125

The lower end of each filling-tube 22 is preferably tapered somewhat to facilitate its insertion within the open top of a bottle-neck,

- and the discharge-opening σ at this end of each filling-tube is contracted or of less diameter than the interior diameter of the tube, which will prevent dribble of liquid held in suspension in a filling-tube by partial vacuum formed in its upper portion when the valve n is closed after the liquid in proper quantity has been passed down from the tank 7 through one or more of the filling-tubes 22.
- 5 An adjustable sleeve 25 is movably held on each filling-tube 22 at a proper distance from the lower end thereof by a nut p , that screws upon the tapered and threaded body of the sleeve, which may be slotted from the smaller end longitudinally, as indicated in Fig. 3, so as to permit a slight compression of the sleeve to be effected by an adjustment of the nut. A headed enlargement is formed on the lower end of each sleeve 25, and this enlargement 15 is rendered convex on the lower surface, as shown at r in Fig. 3. One or more elastic disks 26 are slipped upon the tube 22 below the sleeve 25, and by constriction of the material thereof the disk or disks are held from displacement, and it will be seen that when the filling-tube 22 is introduced within a bottle-neck the disk 26 will effect a tight joint between the tube and bottle-neck, thus preventing any escape of liquid from the latter.
- 20 By projecting the filling-tubes 22 up through the bottom of the depression 7^b the tubes will have guided movement at each end, thus firmly holding the tubes so that their lower ends will be in perfect line and spaced the proper distance apart to insure them entering the bottles. It also prevents likelihood of the tubes being bent and insures the easy working thereof.
- 25 The provision for adjustment of the upper ends of the guide-bars 8 on the ends of the tank 7 affords means for raising or lowering the lower ends of the filling-tubes with regard to the plane of the table 11, and thus compensates for the different heights of bottles placed thereon, which will enable the insertion of the lower ends of said filling-tubes a proper distance into the necks of low bottles or high ones.
- 30 In Fig. 4 is shown an enlarged sectional elevation of the novel filling device provided for the supply of liquid in graduated quantity automatically to the tank 7 when the bottle-filling apparatus is in service, said device being therein shown in closed condition and 35 consisting of the following details: A supply-pipe 27, having a valve-chamber 27^a therein, is secured upon the lower wall of the tank 7, over an opening therein, thus disposing the valve-chamber directly beneath the center of the tank, said supply-pipe, which is shown broken away, being in complete form of a length to connect with a source of liquid-supply under pressure sufficient to insure the liquid freely entering the tank when unobstructed in its passage thereto. A preferably cylindric valve 28 is held to slide vertically in the valve-chamber 27^a and engage two peripheral seats s thereon with annular seats s' , provided within the chamber 27^a, one above the inlet-passage 27^b, that connects the pipe 7^b with the valve-chamber, and the other below said passage.
- 40 In the perforated transverse head-wall 28^a, formed or secured in the elongated cylindric body of the valve 28, near its upper end, the lower end of a valve-stem 29 is secured by threaded engagement or otherwise, as may be preferred. The upper end of the valve-stem 29 passes through a perforation in a guide-bar 7^c, that is transversely disposed in the upper portion of the tank 7 and secured thereto at its ends, whereby the stem is guided to reciprocate freely in a vertical plane.
- 45 At a point which determines the height of the liquid introduced within the tank 7 a float 30, of any preferred material, is held on the stem 29 by collars v or other means. It will be evident that upon the introduction of liquid into the tank through the valve-chamber 27, while the valve 28 is depressed by its weight and that of the valve-stem, the liquid will continue to rise in the tank until the float 30 is lifted, and thus cause the valve to rise in the chamber far enough to engage its seats s with the seats s' , which will cut off the supply of liquid into the tank until the float is slightly lowered by the removal of liquid from the tank.
- 50 A small plug-valve 31 is secured in a perforation in the lower wall of the valve-chamber 27^a and is normally closed, but may be opened when the device is put out of service for the drainage of liquid that is confined in the valve-chamber 27^a.
- 55 It is found in practice that if a proper supply for the tank 7 is maintained the removal of liquid therefrom will be constantly compensated for and the operation of filling bottles may be continued for an indefinite period of time.
- 60 Assuming that a supply of liquid to be bottled is free to pass into the tank 7 and has attained a proper height therein, the operation is essentially as follows: A tray 32, containing bottles B, arranged at spaced distances apart thereon, is placed upon the table 11, these bottles having such relative positions as will locate each one directly below one of the filling-tubes 22. The foot-lever or treadle 18 is now depressed, and this will correspondingly move the tank 7 downwardly, which will enter each tube 22 within the neck of a bottle B. The downward movement is continued until the disks 26 are seated upon the upper edges of the bottle-necks with sufficient pressure to insure tight joints between the tubes 22 and bottle-necks. As the tank continues to descend the springs 24 will be compressed and the valves n unseated, as the tubes 22 will move upward when they can no longer descend into the bottle-necks. Liquid will now pass down the tubes 22 into the bottles B, while air previously contained therein passes up through the air-escape pipe 23 into

the depression 7^b , and thence through the perforations in the bottoms of said depressions into the upper portion of the tank 7. The filling operation will continue until the rising 5 of the liquid into the necks of the bottles covers the open lower ends of the air-escape pipes 23, which will arrest the discharge of the liquid from the filling-tubes, and this will occur at a point in the bottles depending on 10 the previous adjustment of the sleeve 25 and fare enough below the upper edges of the necks to permit the introduction of the corks therein. The treadle-lever 18 is now permitted to rise gently, which will relax compression of 15 the coiled springs 24 and permit the expansion of said springs to seat the valves n upon the annular seats m' , thus closing the orifices m and sealing the tubes 22, so that pressure of the liquid in the tank 7 will be cutoff there- 20 from and at the same time permitting the tank 7 to rise under stress of the spring or springs 17, which will unseat the disks 26. As soon as the disks 26 have been unseated 25 from the necks of the bottles and while the filling-tubes are still in the necks of the bottles the upward movement of the filling-tubes is temporarily checked, when the air in the tank 7 will rush through the air-pipes 23 and force the liquid that has entered the said pipes 30 out into the bottle-necks, thereby effectually clearing the pipes of liquid and preventing the slow dripping of the liquid therefrom, thus insuring a saving of material and promoting cleanliness. The liquid having been 35 expelled from the air-pipes, the filling-tubes are completely removed from the bottles by a full elevation of the tank 7.

In Fig. 6 I have shown a modified form of the lower ends of the filling-tubes 22 to adapt 40 them for proper entrance within the necks of bottles having extremely-small openings. Some bottles have necks, such as B' , that contract in their bores toward their lower ends to very small diameter, where they merge into 45 the bodies of the bottles. To adapt the filling-tubes for their introduction within such bottle-necks to a proper depth, a nozzle is provided that projects from the lower end of the tube 22. The nozzle for each filling-tube 50 consists of a tapered tube-section 22^a of a length that will permit it to pass down in the bottle-neck, such as B' , and extend below the neck into the bottle-body a short distance, as indicated in Fig. 5. An air-escape pipe 23 is 55 provided for each tube 22 and nozzle 22^a , arranged within said tubular parts, as already described with regard to the filling-tubes used for the ordinary bottle-necks B , and the lower end of each air-escape pipe is affixed in the 60 side wall of the tapered nozzle near the lower end thereof. In this construction the nozzle 22^a is introduced at its upper end a short distance within the lower end of the filling-tube, and the upper end of the nozzle is thickened 65 to increase its external diameter, thereby affording a suitable offset or shoulder v at the

lower end of the filling-tube, whereon the washers or disks 26 may have seated engagement, and thus be adapted to seal the joint between the upper edge of the bottle-neck B' 70 and the side wall of the nozzle 22^a , the operation of filling the bottles being the same as has already been described.

Having thus described my invention, I claim as new and desire to secure by Letters 75 Patent—

1. In a bottle-filling machine, the combination with a bottle-support, of a vertically-slidable filling-tank above the support, sliding and spring-pressed filling-tubes having 80 their lower ends projecting out through the bottom of the tank and their upper ends extending into the upper part of the tank and means in the upper part of the tank for supporting and guiding the upper ends of the 85 tubes, said tubes each being provided with an inlet-opening which is normally below the inner surface of the bottom of the tank, substantially as described.

2. In a bottle-filling machine, the combination with a bottle-support, of a vertically-slidable filling-tank above the support, sliding and spring-pressed filling-tubes having 90 their lower ends projecting out through the bottom of the tank and their upper ends extending into the upper part of the tank and having guided movement therein, each of the tubes being provided with an inlet-opening which is normally below the inner surface of 95 the bottom of the tank, and an air-vent pipe 100 in each filling-tube, said vent-pipe opening out through the filling-tube near the upper and lower ends thereof, substantially as described.

3. In a bottle-filling machine, the combination with a bottle-support, of a vertically-slidable tank above the support, having openings in its bottom and annular recesses around said openings, sliding and spring-pressed filling-tubes having their lower ends projecting through the openings in the bottom of the tank and their upper ends extending into the upper part of the tank and having guided movement therein, each tube being provided with an inlet-opening and with a valve above 105 said inlet-opening adapted to be seated in the recess of the bottom of the tank, and an air-vent pipe in each filling-tube, said air-vent pipe opening out through the filling-tube near 110 the upper and lower ends thereof, substantially as described.

4. In a bottle-filling machine, the combination with a horizontally-movable bottle-support, of a vertically-slidable filling-tank above the support, a series of sliding and spring-pressed filling-tubes having their lower ends 125 projecting out through the bottom of the tank and their upper ends extending into the upper part of the tank and having guided movement therein, each of the tubes being provided with an inlet-opening and a valve above 130 the inlet-opening, and an air-vent pipe in each

filling-tube, said vent-pipe opening out through the tube near the upper and lower ends thereof, substantially as described.

5. In a bottle-filling machine, the combination of a tank, a spring-actuated support for the tank, a frame whereon the support is adapted to reciprocate, means to depress the tank by foot-pressure, a series of spaced filling-tubes depending through the tank and held to slide therein at the upper and lower sides of said tank, and each having a contracted escape-aperture in its lower end, a sealing-cap at the upper end of each tube, an inlet-orifice in each filling-tube located near the inner surface of the bottom wall of the tank, an annular valve on each tube adapted to close the inlet-orifice therein when the tube is depressed, a spring on each tube pressing the tube and the valve thereon downwardly, and an air-escape pipe extending interiorly from near the lower end of each filling-tube to near the top thereof and tapping the side of said tube, the air-inlet for the lower end of the pipe being above the outlet of the filling-tube.
- 25 6. In a bottle-filling machine, the tank-filling device, comprising the liquid-supply pipe, the valve-chamber on one end of said supply-pipe covering an opening in the tank, the cylindrical hollow valve therein, having two circumferential valve-seats thereon, the valve-rod extended from the top of the valve up loosely through a guide-bar, and the float held on the valve-rod within the tank.
7. In a bottle-filling machine, the combination with a tank provided with a cup-like depression in its cover, having communication with the tank, of a sliding and spring-pressed filling-tube having its lower end projecting through the bottom of the tank and its upper end projecting into the cup-like depression of the tank, and an air-vent pipe in the filling-tube and having its upper end opening out through the tube in the cup-like depression and its lower end opening out through the pipe near the lower end thereof, substantially as described.

8. In a bottle-filling machine, the combination with a tank provided with a cup-like depression in its cover, communicating with the tank, of a filling-tube having its upper end projecting through the bottom of the said de-

pression and its lower end projecting out through the bottom of the tank, and a spring surrounding the tube between the bottom of the said depression and a collar on said tube, substantially as described.

9. In a bottle-filling machine, the combination with a tank having a cup-like depression in its cover, communicating with the tank, and provided with an opening in its bottom, of a filling-tube having its upper end projecting into the cup-like depression and its lower end projecting out through the opening in the bottom of the tank, said tube being provided with an inlet-opening and with a valve above said opening, and a spring surrounding the filling-tube between the bottom of the depression and a collar on the tube, substantially as described.

10. A bottle-filling machine, comprising a supporting-frame, a horizontally-movable bottle-support mounted in the frame, a vertically-slidable filling-tank mounted in the frame above the support, a float-valve for automatically controlling the supply of liquid to the tank, a series of sliding and spring-pressed filling-tubes having their upper ends extending into the upper part of the tank above the level of the liquid, and their lower ends projecting out through the bottom of the tank, and air-vent pipes in the filling-tubes and opening out through the same near the ends thereof, substantially as described.

11. In a bottle-filling machine, the combination with a tank, and filling-tubes having their upper ends projecting up into the upper part of the tank, and their lower ends projecting out through the bottom of the tank, of an air-vent pipe for each tube, said pipes being arranged in the tubes and having their end opening out through the side of the tube near the upper and lower ends thereof, substantially as and for the purpose set forth.

In testimony whereof I have signed my name to this specification in the presence of two subscribing witnesses.

SAMUEL C. MILLER.
